(57) **CLAIM**

We claim, the ornamental design for a paper product dispenser, as shown and described:

DESCRIPTION

FIG. 1 is a front perspective view of a paper product dispenser, showing our new design;

FIG. 2 is a front elevation view thereof;

FIG. 3 is a side elevation view thereof taken from the right of FIG. 2;

FIG. 4 is a top plan view thereof;

FIG. 5 is bottom plan view thereof;

FIG. 6 is a side elevation view thereof taken from the left of FIG. 2;

FIG. 7 is a rear elevation view thereof;

FIG. 8 is a front perspective view thereof in another embodiment;

FIG. 9 is a front elevation view thereof;

FIG. 10 is a side elevation view thereof taken from the right of FIG. 9;

FIG. 11 is a top plan view thereof;

FIG. 12 is bottom plan view thereof;

FIG. 13 is a side elevation view thereof taken from the left of FIG. 9;

FIG. 14 is a rear elevation view thereof;

FIG. 15 is a front perspective view thereof in another embodiment;

FIG. 16 is a front elevation view thereof;

FIG. 17 is a side elevation view thereof taken from the right of FIG. 16;

FIG. 18 is a top plan view thereof;

FIG. 19 is bottom plan view thereof;

FIG. 20 is a side elevation view thereof taken from the left of FIG. 16; and,

FIG. 21 is a rear elevation view thereof.
